[57] CLAIM

The ornamental design for a data binder hanger, as shown and described.

DESCRIPTION

FIG. 1 is a perspective view of a data binder hanger showing our new design, the environmental structure shown in dotted lines being for illustrative purposes only and not a part of the design claimed;

FIG. 2 is an enlarged scale perspective view of the data binder hanger;

FIG. 3 is a side elevational view thereof;

FIG. 4 is a top plan view thereof;

FIG. 5 is a bottom plan view thereof;

FIG. 6 is a left end elevational view thereof; and

FIG. 7 is a right end elevational view thereof.
